HORIZONTAL BORING MACHINE

John D. Osborn, Houston, Tex.

Application June 29, 1956, Serial No. 42,091

Term of patent 14 years

(Cl. D63—1)

Fig. 1 is a perspective of a horizontal boring machine showing my new design, and

Fig. 2 is a cross-sectional view on the line 2—2 of Fig. 1.

I claim:

The ornamental design for a horizontal boring machine, as shown.
